UNITED STATES PATENT OFFICE.

MATTIE S. CLENDENIN, OF MEXICO, MISSOURI.

BANDAGE.

No. 880,718.

Specification of Letters Patent.

Patented March 2, 1892.

Application filed June 1, 1897. Serial No. 376,800.

To all whom it may concern:

Be it known that I, MATTIE S. CLENDENIN, a citizen of the United States, residing at Mexico, in the county of Audrain and State 5 of Missouri, have invented certain new and useful Improvements in Bandages, of which the following is a specification, reference being had therein to the accompanying drawing.

My invention relates to improvements in 10 bandages for correcting double chins and preventing the formation of lines around the mouth and it consists of the features of novelty hereinafter described and claimed.

The object of the invention is to provide 15 a chin bandage of this character which is so shaped that it will effectively accomplish its intended purpose and which may be readily applied and worn at any time without inconvenience or discomfort.

20 The above and other objects are attained in the preferred embodiment of my invention illustrated in the accompanying drawings, in which

Figure 1 is a view illustrating the application of the bandage; and Fig. 2 is a perspective view of the bandage.

The bandage comprises upper and lower longitudinally curved straps 1, 2 having their ends converging and united, as at 3, 30 and their inner intermediate portions separated to provide an opening 4. By constructing the bandage in this manner it may be readily applied to the chin so that the longer and lower strap 2 will engage the 35 bottom of the chin and the shorter and upper strap 1 the front of the chin, while the end or point of the chin will be disposed in the opening 4. The lower strap 2 is comparatively broad and its front edge is ex- 40 tended at its center to provide a V-shaped projecting portion 5; so that the fleshy part of the chin will be effectively supported by the bandage. The upper strap 1 is of such width that it will support the flesh upon the 45 front of the chin and at the sides of the mouth and thus prevent the formation of mouth lines, and at the center of its bottom edge is formed a V-shaped notch 6 which receives the lower end or point of the chin 50 and permits the upper strap to more effectively accomplish its intended purpose. The ends 3 of the bandage are formed with inwardly extending V-shaped notches 7 to receive the ears and to provide projecting 55 arms or end portions 8 which project above and below the ears and have attached to

them ribbons or the like 9 adapted to be tied over the head of the wearer, as clearly shown in Fig. 1. The bandage is composed of elastic webbing and is preferably woven 60 in a single piece, as illustrated in the drawings. It may be made of other elastic material and, of course, in various sizes to fit chins of different sizes and shapes.

From the foregoing it will be seen that by 65 constructing the bandage as above described, it will closely fit the bottom and front portion of the chin and the jaws and also the fleshy upper part of the throat so that its use 70 will effectively prevent the formation of a double chin and also lines around the mouth. The provision of the opening 4 and the shaping of the lower strap to provide the projecting portion 5 and the shaping of the upper strap to provide the notch 6 causes the bandage 75 to properly fit the chin, and the provision of the V-shaped notch 8 in the ends of the bandage permit the latter to be stretched after it is applied and to support the fleshy parts of the face at the rear of the lower jaw. 80

Having thus described my invention what I claim and desire to secure by Letters Patent is:

1. A bandage of the character described comprising a body of elastic material formed with a longitudinal slot to receive the point of the chin and to provide upper and lower supporting straps, the upper strap being adapted to engage the front portion of the chin beneath the lower lip and being formed in its lower edge with a centrally disposed and substantially V-shape notch, the lower strap being adapted to engage the bottom and side portions of the chin and jaw and being formed at its front edge with a centrally disposed and substantially V-shaped projection, and attaching ribbons connected to the ends of said body, substantially as and for the purpose set forth. 90

2. A bandage of the character described comprising a body of elastic material formed with a longitudinal slot to receive the point of the chin and to provide upper and lower supporting straps, the upper strap being adapted to engage the front portion of the chin beneath the lower lip and being formed in its lower edge with a centrally disposed and substantially V-shape notch, the lower strap being adapted to engage the bottom and side portions of the chin and jaw and being formed at its front edge with a centrally disposed and substantially V-shaped 100

projection, the ends of the body being formed with centrally arranged V-shaped notches adapted to receive the lower ends of the ears and to provide projecting arms, and attaching ribbons secured to said arms for holding the bandage in position, substantially as and for the purpose set forth.

In testimony whereof I hereunto affix my signature in presence of two witnesses.

MATTIE S. CLENDENIN.
